UNITED STATES PATENT OFFICE.

LEANDER D. WHEATLEY, OF WAITSBURG, WASHINGTON, ASSIGNOR OF ONE-HALF TO
FRANK A. JONAS, OF WAITSBURG, WASHINGTON.

IDENTIFICATION OR MARKING TAG.

1,111,629.

Specification of Letters Patent.

Patented Sept. 22, 1914.

Application filed October 9, 1912. Serial No. 724,836.

To all whom it may concern:

Be it known that I, LEANDER D. WHEATLEY, a citizen of the United States, residing at Waitsburg, in the county of Walla Walla 5 and State of Washington, have invented new and useful Improvements in Identification or Marking Tags, of which the following is a specification.

The invention relates to a marking device 10 and more particularly to the class of identification tags, especially designed for use in dyeing and cleaning establishments.

The primary object of the invention is the provision of a tag of this character where- 15 in the necessity of a string or other fastener is entirely dispensed with, yet the said tag can be conveniently and quickly engaged on a button on a garment so that the latter can be readily identified.

20 Another object of the invention is the provision of a tag wherein the button on a garment or other article can be easily engaged in the eye of the tag so as to secure the same thereon without the liability of tearing the 25 said tag or pulling the button from the garment or article.

A further object of the invention is the provision of a tag of this character which is simple in construction, strong, durable, reliable and efficient in its purpose, and also 30 inexpensive in manufacture.

With these and other objects in view the invention consists in the construction, combination and arrangement of parts as will 35 be hereinafter more fully described, illustrated in the accompanying drawing and pointed out in the claim hereunto appended.

In the drawings: Figure 1, is a plan view 40 of a tag constructed in accordance with the invention. Fig. 2, is a vertical longitudinal sectional view thereof. Fig. 3, is a longitudinal section view of the tag when applied to a button on a garment. Fig. 4, is a fragmentary perspective view of the tag with 45 the eye open for receiving the button.

Similar reference characters indicate corresponding parts throughout the several views in the drawing.

Referring to the drawing by numerals, the tag comprises a blank 5 preferably constructed from stiff paste board, the same being of the desired thickness, although the blank may be made from any other suitable material if desired and is of oblong shape, it being understood of course that the blank 55 should have a certain amount of flexibility, so as to assure wear and durability. The blank 5 near one end is formed with a substantially V-shaped slot 6, to provide a button hole or eye, the branches of the slot 60 being outwardly curved as at 7, so as to allow the free insertion of a button therein when it is attached to a garment or article to be marked or identified by said tag. The medial portion of the slot 6 communicates 65 with a circular opening or aperture 8, which is designed to accommodate the thread connecting the button to the garment or article after the said button has been fully inserted through the said slot for the securing of the 70 tag thereon. Glued or otherwise secured to opposite faces of the blank 5 about the slot 6 therein are reinforcing plies 9, which are provided with slots and openings 10 and 11, respectively, corresponding to the slot 6 75 and opening 8 in said blank, the plies being designed to prevent the tearing of the blank at the slot 6 and opening 8, during rough use of said tag or the careless handling thereof when securing the same to a button. 80

What is claimed is:—

A tag provided with an opening comprising a reduced neck intermediate the ends with diverging lines upon one side of the neck and a line defining the major arc of a 85 circle upon the opposite side of the neck and an integral tongue filling the neck and the space between the diverging lines and provided with an extremity substantially completing the circle. 90

In testimony whereof I affix my signature in presence of two witnesses.

LEANDER D. WHEATLEY.
